UNITED STATES PATENT OFFICE

106,901

DESIGN FOR A COMBINED COMB SUPPORT AND RAZOR BLADE DEPOSITORY

Howard Pena, Chicago, Ill.

Application July 14, 1937, Serial No. 70,436

Term of patent 7 years

To all whom it may concern:

Be it known that I, Howard Pena, a citizen of the United States, residing at Chicago, in the county of Cook and State of Illinois, have invented a new, original, and ornamental Design for a Combined Comb Support and Razor Blade Depository, of which the following is a specification, reference being had to the accompanying drawing, forming a part thereof.

On the drawing,

Fig. 1 is a perspective view of a combined comb

support and razor blade depository showing my new design;

Fig. 2 is a similar perspective view looking from the back side thereof, and

Fig. 3 is a sectional view taken generally on the lines 3—3 of Fig. 2.

I claim:

The ornamental design for a combined comb support and razor blade depository as shown.

HOWARD PENA.
